FIG. 8

FIG. 1 is a top plan view of a pair of eyeglasses showing my new design;

FIG. 2 is a front view thereof;

FIG. 3 is a perspective view thereof;

FIG. 4 is a side view thereof taken from the right side of the eyeglasses shown in FIG. 2, the side not shown being substantially of the same appearance as the side shown;

FIG. 5 is a top plan view of a modified form of the pair of eyeglasses shown in FIG. 1;

FIG. 6 is a front view of said modified form;

FIG. 7 is a perspective view of said modified form; and

FIG. 8 is a side view of the modified form taken from the right side of the eyeglasses shown in FIG. 6, the side not shown being substantially of the same appearance as the side shown.

The present application is a continuation of my prior co-pending design applications Serial Nos. D-77,888 and D-77,889, both filed December 23, 1963, now abandoned.

I claim:

The ornamental design for a pair of eyeglasses, substantially as shown and described.
